[57] CLAIM

The ornamental design for a thumb pad for controlling the operation of a toy vehicle in a vehicle control system, as shown and described.

DESCRIPTION

FIG. 1 is a top, side perspective view of a thumb pad for controlling the operation of a toy vehicle in a vehicle control system showing our new design, the broken lines are for illustrative purposes only and form no part of the claimed design;

FIG. 2 is an elevational view of the right side thereof;

FIG. 3 is an elevational view of the left side thereof;

FIG. 4 is a top plan view thereof;

FIG. 5 is an elevational view of the front thereof;

FIG. 6 is an elevational view of the rear thereof; and,

FIG. 7 is a bottom plan view thereof.
